Inventor E. W. Marshall

UNITED STATES PATENT OFFICE.

THOMAS L. DENNIS, OF PRINCE BAY, NEW YORK.

BOAT PROPELLING AND STEERING DEVICE.

1,130,153.

Specification of Letters Patent.

Patented Mar. 2, 1915.

Application filed April 21, 1914. Serial No. 833,364.

To all whom it may concern:

Be it known that I, THOMAS L. DENNIS, a citizen of the United States of America, and a resident of Prince Bay, Richmond county, 5 and State of New York, have invented certain new and useful Improvements in Boat Propelling and Steering Devices, of which the following is a specification, reference being had to the accompanying drawings, 10 forming a part thereof.

My invention relates to improvements in boat propelling and steering devices, and its object is to provide a simple and efficient apparatus which may be used as an oscillating sculling device for propelling a boat, or 15 as a rudder for steering the boat to which it is applied. These and other advantages of my invention will be set forth in the following specification in which the invention will 20 be described and the novel features thereof will be set forth in appended claims.

Referring to the drawings: Figure 1 is a side elevation partly in section of a device which embodies my invention, shown applied to the stern of a boat, a portion of 25 which is shown in this figure in section. Fig. 2 is a sectional plan view of the same parts, the section being taken on the line 2-2 of Fig. 1. Fig. 3 is a plan view of the 30 apparatus with the lock in use illustrating the use of the device as a rudder. Fig. 4 is a plan view of a modified detail of construction.

Like characters of reference designate 35 corresponding parts in all the figures.

10 designates a portion of a boat to the stern of which my device is attached.

11 is a bracket which is affixed to the boat in some suitable manner as, for example, by 40 bolts 12. The casing forms a sleeve bearing 13 for an actuating rock shaft 14, to the forward end of which is affixed a hand lever 15. The parts may be so disposed in relation to the boat that the shaft 14 is parallel 45 with its keel and under the thwarts or seats. The lever 15 may be just forward of a midship thwart so as to be within easy reach of an operator seated upon such thwart and facing forward.

50 Forward of the sleeve 13 is a collar 16 on shaft 14 and back of the sleeve is an angular member 17 in one arm of which is a hole into which shaft 14 projects and a set screw 18 affixes the member 17 to the shaft. 55 Through the other arm of the angular member is bored a hole at right angles to shaft

14, which forms a bearing for a swinging shaft 20.

The swinging shaft 20, is shown in its vertical position in Figs. 1 and 2. Near its lower end it is slotted to straddle a flat blade 21 which is pivoted to it at 22. A vertically 60 slideable collar 23 is mounted upon the shaft 20 and may be affixed thereto in suitable position by a thumb-screw 24. Between it and the blade 21 is a connecting rod 25 by 65 means of which the blade may be held relatively to shaft 20 in the position in which it is shown in full lines in Fig. 1, or may be swung about its pivot to the position in 70 which it is indicated in dotted lines in the same figure at 21^A.

Affixed to the shaft immediately above the member 17 is a collar 30 which limits the downward position of the shaft. This collar is constructed with two prongs 31 which are situated at opposite sides of a pin 19 which projects upwardly from the member 17. These prongs limit the amount of rotation which the shaft 20 may have in the angular member 17. I prefer to provide also 75 a spring 32, the ends of which are situated at opposite sides of the pin 19 but nearer to it than are the prongs 31, which spring passes around the collar 30 and is affixed to a flattened portion thereof at the after-side by a 80 clip and bolt 33.

Before specifically describing the other parts of the device which are illustrated in the drawings, I will point out the manner in 90 which the parts which already have been described, operate as a propeller to scull the boat. Let us assume that the operator first pulls up on that end of lever 15 which in Fig. 2 is designated by the letter B. This 95 will swing the lower end of shaft 20 to the right. The blade 21 will not follow this movement readily but will lag behind causing a partial rotation of shaft 20 in the member 17 in the direction indicated by the 100 arrow. This rotation will be arrested by the spring 32 and limited by one of the prongs 31 when the blade has reached the desired angle relative to the keel of the boat. Further rotation of shaft 14 by the operator will 105 cause the action of the blade 21 on the water to propel the boat forward. Now the operator pulls up on the end C of the lever 15. The first effect of this will be to swing the blade to the other side of shaft 20 and then 110 to produce a forward propelling thrust upon the boat. By repeating this operation the

boat may be sculled readily with the operator in an easy bow-facing position, and to a certain extent the boat may be guided by pulling harder on one side of lever 15 than on the other, because for every forward thrust of the blade there is a component side thrust which the operator may make stronger on one side than on the other. The spring 5 may of course be omitted if desired, but it 10 cushions the strokes and prevents any slamming and jarring of the parts. It is also possible to omit the prongs 31 and to depend upon the spring alone to limit the rotation of the shaft 20. When it is desired to reverse 15 the boat and propel it backward, the collar 23 is loosened and moved to its lower position in which it is indicated in dotted lines in Fig. 1 when the blade 21 will lie forward of the shaft 20. Now the oscillation of shaft 20 20 will cause the partial rotation of shaft 20 as before but in opposite directions and the propelling thrust then generated will be astern.

If instead of the pivoted blade shown in 25 Figs. 1, 2 and 3, a more simple arrangement for reversing is desired, the blade such as 34 in Fig. 4, may be rigidly affixed to shaft 20 and a double-pronged collar 35 used instead of collar 30. The prongs 36 perform the 30 same function as do the prongs 31 in the other structure, but when it is desired to scull backward, the shaft 20 is lifted until the prongs clear the pin 19 and is then turned around 180 degrees, blade and all, 35 and let down again with prongs 37 lying at opposite sides of the pin. The position of the pin relative to the collar 35 in this new position is indicated in dotted lines at 19^A in Fig. 4. The upper part of bracket 11 is constructed to form a support for a sliding bolt 40 or latch 40, the outer end of which is forked as at 41. Affixed to shaft 20 opposite bolt 40 is a collar 42 which has a forwardly projecting arm 43. When this device is to be used 45 as a rudder, the bolt is slid back until its forked end 41 embraces the end of arm 43. Under these conditions, rocking shaft 14 in one direction or the other will cause the blade 21 to be swung positively a desired 50 amount, to one side or the other of shaft 20.

To describe the operation more specifically, attention is called to Fig. 3. When shaft 14 is rotated by an upward pull on end B of lever 15, the upper end of shaft 20 is moved 55 to the left, as shown at D. But the forward end of arm 43 cannot now make a corresponding movement and consequently the shaft 20 and blade 21 will be moved in a clockwise direction, and the blade will assume the position 60 in which it is shown at 21^B. An opposite rotation of shaft 14 will cause the blade to assume the position in which it is shown at 21^C. In this manner the device may be used as a rudder.

65 This apparatus may be applied to small

boats such as are usually rowed by oars or sculled by a single oar. Or it may be applied to sail boats in place of their usual rudders. In the latter case it is obvious that such a boat if becalmed may be propelled 70 without the expense and inconvenience of installing an auxiliary engine to meet such emergency.

The invention is capable of many modifications of structure and I intend no limitations other than those set forth in the appended claims. 75

What I claim is:

1. In a propelling and steering device for boats, the combination of a longitudinal 80 rock shaft, a transverse shaft rotatively mounted at the end thereof, means for limiting the rotative movement of said transverse shaft, a blade on said shaft projecting from one side thereof, and means for 85 moving the blade to the opposite side of the shaft relative to the boat.

2. In a propelling and steering device for boats, the combination of a longitudinal 90 rock shaft, a transverse shaft rotatively mounted at the end thereof, means for limiting the rotative movement of said transverse shaft, a blade pivotally supported on 95 said shaft and projecting to one side thereof, and means for swinging the blade about its pivotal support to the opposite side of the shaft.

3. In a propelling and steering device for boats, the combination of a longitudinal 100 rock shaft, a transverse shaft rotatively mounted at the end thereof, means for limiting the rotative movement of said transverse shaft, a blade pivotally supported on 105 said shaft and projecting to one side thereof, a vertically slidable collar on the transverse shaft, a connecting rod between said collar and the blade, and means for adjusting the vertical position of the collar to thereby 110 swing the blade about its pivotal support to one side or the other of the transverse shaft.

4. In a propelling and steering device for boats, the combination of a longitudinal 115 rock shaft, a transverse shaft rotatively mounted at the end thereof, means for limiting the rotative movement of said transverse shaft, a blade on said transverse shaft, an arm projecting from the transverse shaft above the axis of the rock shaft, and means for preventing transverse movement of the 120 end of said arm to thereby cause the swinging movement of the transverse shaft to rotate said transverse shaft and its blade.

5. In a propelling and steering device for boats, the combination of a longitudinal 125 rock shaft, a transverse shaft rotatively mounted at the end thereof, means for limiting the rotative movement of said transverse shaft, a blade on said transverse shaft, an arm projecting from the transverse shaft 130

above the axis of the rock shaft, and means comprising a sliding latch having a bifurcated end adapted to embrace the end of said arm for preventing transverse movement of the end of said arm to thereby cause the swinging movement of the transverse shaft to rotate said transverse shaft and its blade.

In witness whereof, I have hereunto set my hand in the presence of two subscribers, this 18 day of April, 1914.

THOMAS L. DENNIS.
